UNITED STATES PATENT OFFICE.

KARL GUSTAV LENNART HÖGEL, OF STOCKHOLM, SWEDEN.

AUTOMATIC CIRCUIT BREAKER.

Application filed April 15, 1921. Serial No. 461,848.

To all whom it may concern:

Be it known that I, KARL GUSTAV LENNART HÖGEL, a subject of the King of Sweden, residing at Norra Smedjegatan 84, 5 Stockholm, Sweden, have invented certain new and useful Improvements in Automatic Circuit Breakers, of which the following is a specification.

The present invention relates to an electric 10 circuit-breaker or switch of the kind in which the electric current is automatically interrupted when the medium which surrounds the circuit-breaker has reached a certain temperature.

15 In accordance with the invention, two contacts connected to the circuit conducting wires and situated at a certain distance from one another, and which carry or support between them one or more conductive bodies, 20 serving as circuit-closers, are combined with a rod, arm, link, or the like, in such wise that the rod, on the temperature rising, owing to the deformation to which it is subjected by the rise of temperature, removes 25 the contact pieces further and further apart from one another, so that at a certain temperature the body which serves as a circuit-closer is released, and owing to its weight, or by some other force acting on the body, 30 is carried out of the contact position, so that the current is interrupted.

In order to make plain the invention, some forms thereof are shown in the accompanying drawing. Figs. 1, 2 and 3 show circuit-breakers constructed in accordance with the 35 invention in vertical section; Figs. 4 and 5 show such a circuit-breaker in two vertical projections at right angles to one another. Fig. 6 shows another form of the 40 invention mounted in a contact holder connected to a smoothing iron, shown in end-elevation, the lid of the holder being removed. In the different figures corresponding parts are furnished with the same indicating numbers.

In Figure 1, 1 designates the two contacts which are carried by yielding standards 2, mounted on an insulating bottom plate 3 by means of screws 4, which at the same time 50 serve to fix the connecting wires 5. Between the contacts 1 is inserted a loose body 6 serving as a circuit-closer. Between the standards 2 is tightly fitted a rod 7, insulated from the standards 2 by intermediate pieces 8. The rod 7 consists of some metal or other material which expands on being heated.

The apparatus operates in the following manner: When the rod 7 expands as the temperature rises the contacts 1 are removed further and further apart from one another, 60 until, on a certain temperature being reached, they are separated so far that the body 6 falls down and the current thus is interrupted. As this interruption is effected rapidly, and as moreover the breaking of 65 the circuit takes place at two contact positions, a practically spark-free interruption of the current is obtained.

According to the form shown in Fig. 2, the removal or separation of the contacts 1^a 70 from one another is effected by means of the standards 2^a composed of bimetallic elements, i. e., of two metal strips 11, 12, welded or otherwise fastened together on each other and with different coefficients of expansion, 75 for example brass and iron. The metal or alloy which has the highest coefficient of expansion is in this case placed on the inner side. These standards, when heated, bend outwards from one another, and, on a certain temperature being reached, the interruption of the current takes place in the same way as in the device illustrated in Fig. 1.

According to Fig. 3, the standards 2^b are 85 composed of bimetallic elements 1^b as in Fig. 2, but with the difference that in this arrangement the metal which has the highest coefficient of expansion must be placed on the outside. In this case the standards 2^b are 90 not provided with separate contact pieces fitted thereon: the actual standards, which are shaped in the form of a C, serve at their upper ends as contact pieces. In other respects this device operates in the same manner as that shown in Fig. 2.

In Figures 4 and 5 is shown a circuit-breaker which is arranged in such wise that when the circuit-closing body has fallen and thereby broken the current, it is not necessary to touch the actual body in order to restore it to its position and thereby close the circuit; the circuit is closed merely by turning the entire circuit-breaker through a certain angle. This arrangement entails 100 the advantage that the circuit-breaker can be constructed entirely closed. For this purpose the two parts 1^c serving as contact pieces and also the standards 2^c are made in the shape of arms composed of bi-metallic elements, and so bent as to form pockets 13 105 into which the circuit-closing body falls 110

- when the current is interrupted. These arms are fixed on an insulated plate 3 with the aid of angular clamps or supports 14 to which the conducting wires are connected.
- 5 The plate 3^b is mounted on a horizontal shaft 9 in such a way that it can be rotated in the vertical plane. When the circuit-breaker assumes the position shown in Fig. 4 and the circuit-closing body at a certain 10 temperature falls out of the contact position, it will assume the position 6', indicated with dotted lines, in the pocket 13. From this position the body can be returned to its contact position merely by turning 15 the apparatus at an angle of 180° around the shaft 9. In order to protect the parts which conduct the current, they may be surrounded with a protective casing 10 in which, if desired, an opening may be made opposite 20 the contact position of the body 6 in order to facilitate inspection and to ascertain whether the current is closed or interrupted.
- A circuit-breaker in accordance with the 25 present invention may obviously be performed with other detailed devices than those described or shown on the drawing, while retaining the characteristic features of the invention. The actual circuit-closing 30 body may conceivably be made in the form of a ball, cylinder, or in other suitable forms. It should also be obvious that in the different forms the parts 2 and 2^a may either, as shown in Figs. 1 and 2, be provided with 35 separate contact pieces, or, as shown in Figs. 3 and 4, themselves serve as contact pieces, i. e., be so arranged that the body 6, when the current is closed, rests against a part 1 thereof.
- 40 In Fig. 6 is shown a circuit-breaker, constructed in accordance with this form, mounted in a contact piece or casing connected with the end of a conductor wire, which contact piece is connected to the contact pin on a smoothing iron, which is shown in outline in end view, the lid of the contact piece being supposed to have been removed in order to show the construction more clearly. 30 designates the body of the 45 iron, 14 the two contact pins, which are connected to the resistance coil in the body of the iron. 15 designates the contact piece made of porcelain or other suitable insulating material, which piece is united in a 50 known manner with the end 16 of the conductive wire. The one wire 17 is connected in a known manner to the contact sleeve 18 arranged in the contact piece in a known manner, while the other wire 19 is connected to a screw or a pin 20, to which is 55 fixed a bimetallic body or spring 21, coiled in a spiral, or bent or shaped in some other suitable manner, which spring by the action of a conductive body 22, suitably in the 60 form of a ball or cylinder when in use at

normal temperature, is conductively connected with the contact 23, which in its turn through the wire 24 is conductively connected with the other contact sleeve 25. The contact sleeves 18, 25 are, when in use, 70 connected in a known manner on the pins 14, which are conductively connected with the resistance coil in the iron. Obviously the arrangement of the pins and sleeves may be reversed, the pins being fixed to the contact pieces and connected to the circuit-breaker in the manner indicated above, while the sleeves are arranged in the body to be regulated. If in the use of the iron or of the body, the temperature of which 80 is to be regulated, the temperature should exceed a certain predetermined limit, the bimetallic spring 21, which by radiation or conduction is affected by this rise of temperature owing to its form and composition 85 will contract in such wise that its free end 26, against which the ball 22 rests, will be carried so far apart from the contact 23 that the ball will no longer be retained between the said parts, but will fall down into the 90 position indicated by dotted lines in the lower part of the space or chamber 27 in the contact piece, whereby the supply of current is interrupted, and a superheating of the iron or of the object in question is 95 thus obviated.

When the circuit is again to be closed or the circuit-breaker to be restored to a current-carrying condition, the contact piece 15 is revolved, so that the ball 22 will roll 100 along the wall 28 of the chamber 27 to the working position, i. e., in contact with the spring 22 and the contact 23.

In order to adjust the circuit-breaker to different temperatures, an adjusting-screw 105 29 is fixed in the contact piece, which directly or indirectly acts on the contact 23 (which is so arranged that it normally tends to stand away from the spring), whereby the said contact can be caused to approach 110 the spring, so that the passage for the ball will be smaller, whence a greater contraction in the spring 21, and thus also a higher temperature is required for causing the breaking of the current.

115 This form has proved to be specially suitable for the purpose in question. In this specification and in the following claims the word metal is used as comprising also alloys of metals. It is, of course, obvious that 120 various changes and modifications may be made in the form of construction without, however, departing from the spirit or scope of this invention.

Having thus described my invention I declare that what I claim is:

1. An automatic circuit breaker comprising a pair of contacts, a conductive body loosely carried between said contacts, and means associated with said contacts for sep- 130

arating the contacts upon subjection to a predetermined degree of heat.
2. An automatic circuit breaker comprising a plate, a pair of yielding standards secured to said plate, a pair of contacts disposed at the upper ends of said standards, a conductive body loosely carried between said contacts, and means disposed between said contacts for separating the same upon subjection to a predetermined degree of heat.

3. An automatic circuit breaker comprising a plate, a pair of yielding standards secured to said plate, a pair of contacts dis-

posed at the upper ends of said standards, a conductive body loosely carried between said contacts, a rod secured between said contacts, a pair of insulating members one at each end of said rod, said rod being expandable upon subjection to heat thereby to separate said contacts and break the circuit.

In testimony whereof I have affixed my signature in presence of two witnesses.

KARL GUSTAV LENNART HÖGEL.
